SENSITIVE FUSE

Raymond L. Graumann, Alexandria, Va.

Application August 3, 1940, Serial No. 350,635

4 Claims. (Cl. 102—79)

(Granted under the act of March 3, 1883, as
amended April 30, 1928; 370 O. G. 757)

1

This invention relates to a sensitive fuze for use in exploding the bursting charge of rotating or spinning projectiles and more particularly to a fuze adapted for use with the spinning type of bomb, certain elements of the fuze being operable by centrifugal force to change the fuze from unarmed condition to armed condition.

Among the several objects of this invention are:

To provide a highly sensitive fuze that is nevertheless safe to handle;

To provide firing means that will be of sufficiently rugged construction to detonate the bomb when the fuze is armed but will yield and not detonate the bomb unless the fuze has been armed by rotation;

To provide a fuze with a minimum number of parts and a maximum simplicity of construction; and

To eliminate the necessity for an air-driven propeller on a projectile to arm the fuze.

In the drawings:

Fig. 1 is a side elevation of a bomb provided with a fuze according to the present invention, with certain parts in section;

Fig. 2 is an axial section of the fuze in the unarmed condition substantially on the line 2—2, Fig. 3;

Fig. 3 is a transverse section of the fuze on the line 3—3, Fig. 2; and

Fig. 4 is a fragmentary view similar to Fig. 2 but with the fuze elements in the armed condition.

As is shown in Fig. 1, my present invention is primarily designed for use with a bomb such as 5 particularly adapted to be launched from aircraft and having tail vanes 6 that are given an angular pitch to cause the bomb to spin about its longitudinal axis when falling, as is indicated by the dot and dash line 7 on the body of bomb 5. The pitch of the vanes 6 may be about 5°, in which case it requires several hundred feet of fall to arm the fuze 8. However, if it is desired that the fuze should be armed in a distance of a hundred feet or so the vanes 6 may be given a pitch of 10°.

The fuze 8 comprises two members 9 and 10 that constitute the body thereof and which, together with operating elements therein, are held in assembled relation by a cover 11 of sheet metal spun over the nose as at 12 and over the shoulder at 13.

The member 10 carries the usual booster charge 14 with a tetryl booster lead 15 connecting therewith. Mounted in a channel 16 in the body

2

member 10, for sliding movement transversely of the axis of the fuze, is the detonator holder 17 carrying the detonator element 18 that is movable into alignment with booster lead 15 when the fuze is armed. The detonator holder 17 is held in unarmed position against stop 19 by spring pressed detents 20 that engage in the hole 21 in the holder 17 and which are releasable from engagement with the holder 17 by centrifugal force. It will be noted that more than one-half the mass of the holder 17 is on the left-hand side of the axis of the fuze as shown in Fig. 2, and hence when the detents 20 are released the centrifugal force will move holder 17 to the left in Fig. 2 and bring the detonator 18 into alignment with booster lead 15. This eliminates the friction between detonator holder 17 and detents 20 that would be present if a spring were used to slide the holder 17.

20 The body member 9 has mounted in it along its axis the firing pin 22 which has a heavy collar 23 adjacent its inner end or point 24 and a light, readily shearable flange 25 adjacent its outer end. In the unarmed condition the spring pressed detents 26 engage the inner face of collar 23 and positively hold the firing pin 22 in unarmed position. On the outer end of firing pin 22 is the impact head 27 seated against the light flange 25 and retained in position on the firing pin by 30 setting the end of the firing pin at 28. If, through accident, the fuze is dropped so that impact head 27 strikes while the bomb is unarmed, the light flange 25 will shear and the impact head will merely slide along the firing pin 22 so that the detonator 18 would not be exploded even though it might fortuitously be aligned with the firing pin and the booster lead 15. When the fuze spins, however, the detents 26 are moved outwardly by 35 centrifugal force and the detonator holder is simultaneously shifted to align the detonator 18 with firing pin 22 and booster lead 15. Firing of the detonator 18 by air pressure on head 27 after the fuze has been armed is prevented by the separator disc 29 disposed between the point 24 of firing pin 22 and the detonator holder 17. However, the separator disc 29 is readily puncturable and offers no impediment to firing the detonator 18 when head 27 impacts upon a target with the fuze in armed condition.

40 While the present invention has been shown and described in connection with a bomb of the spinning type, it is also capable of use in projectiles fired from rifled barrels, of one inch caliber or greater, or in projectiles that are caused 45 by any means to spin during flight.

The invention herein described and claimed may be used and/or manufactured by or for the Government of the United States of America for governmental purposes without the payment of any royalties thereon or therefor.

I claim:

1. A fuze armable by rotation about its axis, comprising a body, a booster charge in said body, an axially extending booster lead connecting with said booster charge, a detonator holder mounted in said body to be translationally slidably transversely of the axis of said body and having a detonator therein to be aligned with said booster lead when said holder is in the armed position, spring pressed detents engaged with said holder to retain said holder in the unarmed position but releasable therefrom by centrifugal force, said holder being moved to armed position by centrifugal force after release of said detents, a firing pin disposed along the axis of said body, said pin having a heavy collar adjacent its inner end and a light shearable flange adjacent its outer end, spring pressed detents engaging the inner face of said collar to hold said firing pin in unarmed position but releasable therefrom by centrifugal force, an impact firing head secured on the outer end of said firing pin seated against the outer face of said light flange and adapted to shear said flange in case of impact on said head when said firing pin is in unarmed position, and a puncturable separator disk between the inner end of said firing pin and said detonator holder.

2. A fuze armable by rotation about its axis, comprising a body, a booster charge in said body, an axially extending booster lead connecting with said booster charge, a detonator holder mounted in said body to be translationally slidable transversely of the axis of said body and having a detonator therein to be aligned with said booster lead when said holder is in the armed position, means engaged with said holder to retain said holder in the unarmed position but releasable therefrom by centrifugal force, said holder being moved to armed position by centrifugal force after release of said means, a firing pin disposed along the axis of said body, said pin having a heavy collar adjacent its inner end and a light shearable flange adjacent its outer end, means engaging the inner face of said collar to hold said firing pin in unarmed position but releasable therefrom by centrifugal force, an impact firing head secured on the outer end of said firing pin seated against the outer face of said light flange and adapted to shear said flange in case of impact on said head when said firing pin is in unarmed position, and a puncturable separator disk between the inner end of said firing pin and said detonator holder.

3. A fuze armable by rotation about its axis, comprising a body, a booster charge in said body, an axially extending booster lead connecting with said booster charge, a detonator holder mounted

in said body to be translationally slidable transversely of the axis of said body and having a detonator therein to be aligned with said booster lead when said holder is in the armed position, spring pressed detents engaged with said holder to retain said holder in the unarmed position but releasable therefrom by centrifugal force, said holder being moved to armed position by centrifugal force after release of said detents, a firing pin disposed along the axis of said body, said pin having a heavy collar adjacent its inner end, spring pressed detents engaging the inner face of said collar to hold said firing pin in unarmed position but releasable therefrom by centrifugal force, an impact firing head secured on the outer end of said firing pin, and means operably connecting said impact head to said firing pin, said connecting means being shearable in case of impact on said head before said detents are disengaged from said heavy flange.

4. A fuze armable by rotation about its axis, comprising a body, a booster charge in said body, an axially extending booster lead connecting with said booster charge, a detonator holder mounted in said body to be translationally slidable transversely of the axis of said body and having a detonator therein to be aligned with said booster lead when said holder is in the armed position, means engaged with said holder to retain said holder in the unarmed position but releasable therefrom by centrifugal force, said holder being moved to armed position by centrifugal force after release of said means, a firing pin disposed along the axis of said body, means engaging said firing pin to hold said firing pin in unarmed position but releasable therefrom by centrifugal force, an impact firing head secured on the outer end of said firing pin, and means operably connecting said impact head to said firing pin, said connecting means being shearable in case of impact on said head before said firing pin engaging means is released.
